CORNEAL LENS COMPUTER

Alvin Eugene Reynolds, Tulsa, Okla., assignor to Plastic
Contact Lens Company, a corporation of Illinois

Filed July 3, 1961, Ser. No. 65,793

Term of patent 3½ years

(Cl. D57—1)

FIG 1

FIG 2

FIG 3

FIG 4

FIGURE 1 is a perspective view of a corneal lens computer showing my new design.

FIGURE 2 is a top plan view thereof.

FIGURE 3 is a side elevational view of the corneal lens computer.

FIGURE 4 is a front elevational view of the corneal lens computer.

The rear and side not shown are substantially the same as the respective front and side shown.

I claim:

The ornamental design for a corneal lens computer, substantially as shown and described.
